FOLDING MACHINE

Elmer D. Coston, St. Louis, Mo., assignor to Manufacturers Supplies Company, St. Louis, Mo., a corporation of Missouri

Application December 18, 1946, Serial No. 716,927

5 Claims. (Cl. 12—55)

11

This invention relates generally to machines for folding leather or the like.

While folding machines in considerable variety have heretofore been provided, it has not been easy to adapt the machines of the prior art to the folding of work pieces of different configurations and, while in my prior Patent No. 2,286,467, a folding apparatus was disclosed wherein the parts might be replaced with corresponding parts of different configurations without great difficulty, the apparatus there disclosed required to be operated in a press and necessitated careful adjustment of a number of moving parts in order to achieve satisfactory results.

The object of the present invention, generally stated, is to provide a self-contained folding machine, which may be readily adapted to various configurations of work, which is simple of construction, and which is productive of uniform results.

Other objects will become apparent to those skilled in the art when the following description is read in connection with the accompanying drawings, in which:

Figure 1 is a view in side elevation of an embodiment of the folding machine constructed in accordance with the present invention, less treadle mechanism;

Figure 2 is a longitudinal sectional view of the machine shown in Figure 1 and provided with the treadle operating mechanism;

Figure 3 is a plan view of the apparatus shown in Figure 1;

Figure 4 is a view in front elevation of the machine shown in Figure 1;

Figure 5 is a sectional view taken along line 5-5 of Figure 2;

Figure 6 is an enlarged detail view of the folding part shown in Figure 2 and showing a workpiece in position in the apparatus to be folded;

piece in position in the apparatus to be folded. Figures 7, 8, and 9 are views corresponding to Figure 6 and showing succeeding phases of the folding operation: and

Figure 10 is a partial plan view showing a modified form of hold-down mechanism.

In the embodiment of the invention illustrated in the drawings, the folding machine, as shown in Figure 1, is intended to be mounted upon a table 1 or other suitable support and to be actuated through the succeeding phases of the operation of folding pieces of leather or like material by the manipulation of treadles 2 and 3, each of which is connected with moving parts of the machine, to be described hereinafter.

Upon a base 4 is mounted an organization of

2

mechanism, including a pressure member, which is adapted for limited movement in a vertical direction, and another organization, including a work support (together with a work piece) and a hold-down mechanism, adapted to be moved in a horizontal direction. The operation of these respective horizontally and vertically moving organizations is accomplished by proper manipulation of the treadles 2 and 3.

10 The vertically moving organization includes a head 5 supported at its ends upon bolts 6, which are slidably received within bosses 7 on base 4. Below the bosses 7, the bolts 6 are interconnected by a bar 8. As will be observed from Figure 5, 15 each of the bolts 6 is provided with a sleeve 60 so as to fix the position of head 5 and bar 8 relative to the bolts. About each of the bolts 6 is a coil spring 9 arranged to bias the head 5 in an upward direction relative to base 4.

20 Extending across the base 4 is a shaft 10 having cams 11 at opposite ends thereof. The cams

are arranged for peripheral engagement with wear plates 12 secured to bar 8.

A crank arm 13 is suitably secured to cam-shaft 10 to prevent relative movement between said parts. A pitman 14 connects crank arm 13 with treadle 2, so that, upon depression of treadle 2, head 5 is drawn downwardly against the action of spring 9.

30 For limiting the upward travel of the head 5 and its adjunct parts just described, a plate 15, extending from bar 8, is arranged to engage the end of a set screw 16 mounted in base 4 (see Figure 2).

35 The horizontally movable organization of parts is actuated through a work support 17, which is slidably mounted upon the upper surface of base 4 and has a projection 18 extending through a hole 19 in the upper surface of base 4. The hole 19 is shaped with reference to projection 18 so as to guide the latter in its horizontal translation. Projection 18 is connected with treadle 3 through a chain 20 operating over roller 21 so that, upon depression of the treadle 3 in a counterclockwise direction, the projection 18 with work support 17 and all adjunct parts will be moved rightwardly from the position shown in Figure 2.

50 Mounted upon the work support 17 and arranged to translate therewith is a pair of brackets 22, to each of which is journaled a pair of links 23, 24, supporting a hold-down carrier 25. The link 24 is provided with a counterweight 26 arranged to substantially balance the hold-down mechanism now to be described.

of 55 Rods 27 extending forwardly from hold-down

carrier 25 support a hold-down mechanism, which includes a gripping member 28 and a forming member 29, the latter being movable relative to the former. The gripping member 28 consists of a thin plate secured to a frame 30. Arranged outside the frame 30 is a frame 31 connected to the frame 30 by a pair of pin-and-slot organizations 32, 33, shown clearly in Figures 6, 7, 8, and 9. The forming member 29 is also a thin plate and rides directly upon the upper surface of gripping member 28, the forming member 29 being secured to frame 31 so as to be slidable back and forth therewith and relative to frame 30 and gripping member 28.

The hold-down carrier 25 and its associated parts may be moved by hand between the position shown in full lines and the position shown in dotted lines. Alternatively, the hold-down carrier may be spring-biased toward the full line position and moved to the dotted line position by depressing treadle 3 clockwise (as seen in Figure 2), the latter being connected through a chain to carrier 25.

In view of the fact that all of the parts 22 to 33, inclusive, are mounted upon work support 17, it is apparent that, upon translation of the work support by manipulation of treadle 3, the parts 22 to 33, inclusive, will likewise translate and, so long as the hold-down mechanism is held in the position shown in full lines in Figure 1, there will be no relative movement between the same and the work support 17 despite translation thereof.

Of the parts above described, only the forming member 29 is required to be changed in accordance with the configuration of the work piece being operated upon. The edge 34 of former 29 is shaped in substantial accordance with the configuration of the folded edge to be produced.

Another set of parts carried by head 5 is, however, to be shaped according to the configuration of the work piece to be operated upon. The presser 35 has a lip 36, the margin of which is shaped according to the configuration of the folded edge on the work piece, and adjacent the lip 36 is a shouldered portion, which constitutes an edge-gauge for the margin of the unfolded work piece. Such shoulder is likewise preferably shaped in accordance with the configuration of the margin of the unfolded work piece. While the shaping of the shoulder adjacent lip 36 is not necessarily throughout in strict accordance with the configuration of the unfolded work piece, it is essential that a plurality of points thereon be so positioned with reference to the margin of the lip 36 and the margin of the work piece that said shoulder may act as an edge-gauge and properly position the piece of material to be folded with reference to the margin of lip 36. In the embodiment shown, the presser 35 is removably mounted on head 5 through an intermediate plate 37 and guides 370.

The presser 35 is provided with a floating gauge 38 movable relatively thereto in a vertical direction only. The gauge 38 is accommodated in a recess 39 in the lower surface of presser 35 when the latter is depressed into engagement with the work support 17, as shown in Figure 6. A plurality of pins 40 extend through holes in presser 35 and plate 37 and are engaged above plate 37 by leaf springs 41, which continuously urge gauge 38 out of recess 39 toward the position shown in Figure 8. Thus, when the presser 35 is elevated, the gauge 38 is forced out of recess 39 and constitutes an obstruction across the gap between the bottom surface of presser 35 and the upper

surface of work support 17. In this position, gauge 38 limits the translatory movement of the work piece and former 29 beneath presser 35. Consequently, it is desirable to shape gauge 38 according to the contour of the folded edge of the work piece.

Referring now to Figures 6, 7, 8, and 9, the several phases of operation through which the apparatus is moved in forming a fold at the edge of a piece of leather will be described. Presser member 35 is first placed in the position shown in Figure 6 of the drawings where the lower surface of presser 35 engages the upper surface of work support 17. This is accomplished by depression of treadle 2. Work piece 42 is then placed, with its edge to be folded, in engagement with the edge-gauge shoulder on presser 35, the hold-down mechanism being at this time in the position shown in full lines in Figure 6. When the work piece 42 is properly adjusted to fit the edge-gauge, the work piece may be permanently clamped by a suitable spring clip 43 mounted upon a plate 44, which latter may be removably secured to the work support 17 and functionally may be considered a part of the work support. With the work piece 42 thus properly arranged relative to lip 36 of presser 35, the hold-down mechanism may be moved to the dotted line position shown in Figure 6 where gripping member 28 engages the surface of the work piece 42 and clamps the same against the work support. Hand pressure is sufficient, in view of the extended surface area of gripper 28 in contact with the work piece, to insure against slippage of the work piece relative to the work support.

Having moved the hold-down mechanism into the dotted line position shown in Figure 6, forming member 29 is advanced to the position shown in Figure 7. This does not disturb the gripping relation between gripper 28 and the work piece 42, but, as the edge 34 of former 29 approaches lip 36 of presser 35, treadle 2 is released and the work piece 42 is bent upwardly between lip 36 and edge 34, as shown in Figure 7. It may be pointed out that the sequence of operations just described is not critical in that presser 35 may be permitted to resume the position shown in Figure 7 before forming member 29 is advanced, or the forming member may be advanced to the position shown in Figure 7, while the presser 35 remains in the position shown in Figure 6.

Having released the treadle 2 so that presser 35 assumes the position shown in Figure 7, and having advanced the forming member 29 so that the margin of work piece 42 is turned upwardly, as shown in Figure 7, treadle 3 is now depressed counterclockwise to effect the horizontal translation of the work support, hold-down mechanism, and work piece. Such horizontal translation turns the margin of work piece 42 back over the edge 34 of former 29 and brings the folded edge of the work piece 42 into engagement with gauge 38, as shown in Figure 8.

The former 29 may now be manually retracted to the position shown in Figure 9 where the edge 34 thereof is clear of presser 35 and treadle 2 depressed again to move presser 35 into the position shown in Figure 9, completing and pressing the fold.

In the embodiment shown in Figure 10, the hold-down mechanism is mounted upon a plate 45 corresponding in position and arrangement to the plate 44, above referred to, which is to say, secured to work support 17 against movement relative thereto during operation of the device.

Plate 45 is provided with a pair of bosses 46 for the reception of hinge pins to connect frame 30, gripper 28, former 29, and frame 31 identically as above described. In this embodiment, the linkage 22-23 and the hold-down carrier 25 are dispensed with. When the work piece is first placed upon the work support, the hold-down mechanism, including the parts 28, 29, 30, and 31, is moved out of the way by rotation about the hinge connection to bosses 46, so as to clear the surface of the work support for placement in proper gauged relation relative to lip 36.

From the foregoing description, those skilled in the art should readily understand the construction and operation of the apparatus and realize the advantages thereof.

While one complete embodiment has been described in detail and a modification of the hold-down mechanism described in addition, it will be readily understood that the invention is not limited to the form of apparatus disclosed, but that it is contemplated that the various parts thereof be subject to considerable variation without departing from the spirit of the invention or the scope of the appended claims.

Having thus described the invention, what is claimed and desired to be secured by Letters Patent is:

1. In a folding machine, a work support, a pressure member having a lip shaped according to the contour of the fold to be made and having a gauge adjacent said lip for positioning the work piece to be folded with relation to said lip, means for moving said pressure member between a position whereat said lip is substantially aligned with and a position whereat said lip is elevated above said work support, a forming member having an edge shaped according to said lip and arranged to engage the work piece exteriorly of but adjacent to said lip, and means for translating said work support and forming member together with the work piece beneath and beyond said lip while the pressure member is in elevated position.

2. In a folding machine, a work support, a pressure member having a lip shaped according to the contour of the fold to be made and having a gauge adjacent said lip for positioning the work piece to be folded with relation to said lip, means for moving said pressure member between a position whereat said lip is substantially aligned with and a position whereat said lip is elevated above said work support, a forming member having an edge shaped according to said lip and arranged to engage the work piece exteriorly of but adjacent to said lip, and means for translating said work support and forming member together with the work piece beneath and beyond said lip while the pressure member is in elevated position, said forming member being mounted for movement relative to said work support in the plane of said translation to permit said forming member to be retracted from beneath said pressure member while the work support and work piece remain

in advanced position beneath said pressure member.

3. In a folding machine, a work support, a pressure member having a lip shaped according to the contour of the fold to be made and having a gauge adjacent said lip for positioning the work piece to be folded with relation to said lip, means for moving said pressure member between a position whereat said lip is substantially aligned with and a position whereat said lip is elevated above said work support, a forming member having an edge shaped according to said lip and arranged to engage the work piece exteriorly of but adjacent to said lip, means for translating said work support and forming member together with the work piece beneath and beyond said lip while the pressure member is in elevated position, and an abutment arranged beneath said pressure member to limit the translation of the work piece therebeneath.

4. In a folding machine, a work support, a pressure member having a lip shaped according to the contour of the fold to be made and having a gauge adjacent said lip for positioning the work piece to be folded with relation to said lip, means for moving said pressure member between a position whereat said lip is substantially aligned with and a position whereat said lip is elevated above said work support, a forming member having an edge shaped according to said lip and arranged to engage the work piece exteriorly of but adjacent to said lip, means for translating said work support and forming member together with the work piece beneath and beyond said lip while the pressure member is in elevated position, and an abutment arranged beneath said pressure member to limit the translation of the work piece therebeneath, said forming member being arranged to recede from adjacent said abutment and beneath said pressure member while the latter grips the fold of the work piece against the work support.

5. In a folding machine, a work support, a pressure member having a lip shaped according to the contour of the fold to be made and having a gauge adjacent said lip, a hold-down including a gripping member and a forming member, the latter being mounted to slide upon the gripping member, said forming member having an edge shaped according to said lip, means for translating said work support and hold-down together with a work piece gripped between said gripping member and said work support, said forming member being freely translatable relative to the other parts moved by said translating means.

ELMER D. COSTON.
